W. N. SECHLER

ARCH SUPPORT

Filed June 22, 1923

Inventor:

William Nye Sechler,

Fig. 5. By Hugh M. Bragges.

Attorney

UNITED STATES PATENT OFFICE.

WILLIAM NYE SECHLER, OF FORT SCOTT, KANSAS.

ARCH SUPPORT.

Application filed June 22, 1923. Serial No. 647,022.

To all whom it may concern:

Be it known that I, WILLIAM NYE SECHLER, a citizen of the United States, residing at the city of Fort Scott, in the county 5 of Bourbon, in the State of Kansas, have invented certain new and useful Improvements in Arch Supports, of which the following is a specification.

This invention pertains to flexible arch 10 supports for the shanks of shoes, and among its especial merits over prior devices of this nature are its greater flexibility and lack of interference with the freedom of the foot movements, the feature of unilateral rigidity 15 for the support of the arch at the same time being preserved.

In the accompanying drawings forming 20 part of this specification, in which like numbers of reference denote like parts wherever

they occur,

Figure 1 is a fragmentary sectional view of a shoe, taken on the line 1-1 of Figure 2, and showing the attached arch support as it appears when viewed from the top;

Figure 2 is a longitudinal vertical sectional view of the same, taken on the line 2-2 of Figure 1;

Figure 3 is a transverse vertical sectional view, taken on the line 3-3 of Figure 1;

Figure 4 is a plan view of an alternate form of arch support embodying this invention;

Figure 5 is a longitudinal vertical sectional view of the same, taken on the line 35 5-5 of Figure 4; and

Figure 6 is a transverse vertical sectional view, taken on the line 6-6 of Figure 4.

Referring to the preferred form of this invention, as shown in Figures 1, 2, and 3, a shoe 1, having uppers 2, insole 3, outsole 4, and heel 5, contains within its shank 6, between the insole 3 and the outsole 4, the support 7, consisting of intermediate links 8, a heel link 9, and a fore link 10, the said links 40 8, 9, and 10 being curved to conform to the shape of the arch. Heel link 9 and fore link 10 have holes 11, which register with holes 12 in the outsole 4. Rivets 13 pass through the holes 11 and 12 and secure links 9 and 45 10 to the inner side of outsole 4, the heads 14 of the rivets preferably being against the outsole, while the flattened ends 15 abut against the links 9 and 10.

Links 8, 9, and 10, of plates 16, preferably 50 of sheet metal, having fore edges 17, ter-

minated by perpendicular side edges 18, which are joined to the converging edges 19 terminated at their opposite ends by the rear edge 20, thus forming a tapered tongue 21 at the rear of each of the plate links 8, 9, 60 and 10. Ribs 22 rise perpendicularly from the plate links 8 and 9 at their fore edges 17, and slots 23 separate the intermediate part of each of the ribs 22 from its plate 16, only the end portions 24 of the ribs 22, 65 being joined to the plates 16.

The tapered tongue 21 of fore link 10 fits into the slot 23 of the adjoining intermediate link 8, the tongue 21 of the said link 8 fitting into the slot 23 of the next link 8, and 70 so on, according to the number of intermediate links 8 used in the particular support, the tongue of the last intermediate link 8 fitting into the slot 23 of the heel link 9.

When the wearer of the shoe is in a standing posture, the shoe is in the position shown in full lines in Figure 2, and the bottom sides 25 of the inserted tongues 21 do not abut squarely against the top surfaces 26 of the plates 16, but are slightly inclined 80 thereto, the weight of the body bearing chiefly on the heel 5 and only slightly on the arch and the ball of the foot. If now, as in walking, one foot be lifted from the floor, and the body thrown forward, with its entire weight on the other foot, the heel 5 of the other foot is raised, as shown in dotted lines in Figure 2, and the normal tendency is to straighten out the concavity of the shank of the shoe and of the arch support, 85 but this tendency is checked after a slight yield, by the opposing action due to the bottom sides 25 of the tongues 21 having been brought squarely against the top surfaces 26 of the plates 16. In this position, the 90 weight of the entire body bears on the arch and the ball of the foot. The arch of the foot is, however, firmly supported when the heel is raised, as well as more yieldingly when the heel is on the floor, because of the 95 slot-and-tongue connection forming a hinge, which permits free movement to increase the concavity of the arch, but limits the extent to which the concavity of the arch may be reduced. The tapered edges 19 permit 100 lateral angular movement of the links 8, 9, and 10 with reference to one another, this movement occurring when the support is in the position shown in full lines in Figure 2, as well as when the support is taut, 105 110

as shown in dotted lines, with the tapered edges 19 abutting against the end edges 27 of the slots 23.

It is not, of course, necessary that the 5 tongues 21 all extend in the same direction. For instance, the device may be constructed with the tongues extending in opposite directions, as shown in the alternate form depicted in Figures 4, 5, and 6. Here an intermediate rectangular link 28 has slots 29 at opposite ends, in which fit the tongues 30 of the heel link 31 and fore link 32, having holes 33 for the reception of rivets with which they may be secured to the outsole of 15 the shoe. Link 28 is strengthened by ribs 34 and has a central depressed portion 35 on which rest the tongues 30 passing through the slots 36.

The fore links 10 and 32 of both forms 20 respectively are preferably concave on their top sides, so that they will fit the sole at the ball of the foot.

It has been determined by experience that the use of one intermediate link or more between the heel link and the fore link results 25 in greater flexibility and greatly facilitates the accommodation of the support to the movements of the foot.

Having thus described this invention, I 30 hereby reserve the benefit of all changes in form, arrangement, order, or use of parts, as it is evident that many minor changes may be made therein without departing from the spirit of this invention or the scope of 35 the following claims.

I claim:

1. In an arch support the combination of a plurality of links, the said links being joined to permit free movement in one direction and to restrict the extent of movement in the opposite direction, the joint between the links providing a wedging action in one direction of movement thereof.

2. In an arch support the combination of a pair of plates, one of said plates having a recess and the other of said plates having a tongue tapered in its width and co-operating with the said recess for limiting movement of the tongue in the recess. 45

3. In an arch support the combination of a pair of links, one of said links having a tongue, and the other of said links being formed of a plate having a rib, and a slot at the junction of said plate with said rib, the said slot co-operating with the said 55 tongue. 50

4. The combination of a shoe and an arch support, the said arch support having a fore link, a heel link, and an intermediate link, the said fore and heel links being riveted to the outsole of the shoe and a sliding connection between the links including a slotted rib carried by two of the links and a tongue carried by the other link and intermediate link. 60 65

5. In an arch support, the combination of a plurality of loosely connected links, the outer end links being anchored within a shoe, the connection between the links including a slotted perpendicular rib carried 70 by one end of each link and a tongue carried by the adjacent end of the next link and freely extending into the slot.

6. In an arch support, the combination of a plurality of loosely connected links, the outer end links being anchored within a shoe, the connection between the links including a slotted perpendicular rib carried 75 by one end of each link and a tongue carried by the adjacent end of the next link 80 and freely extending into the slot, the tongue being of tapering formation to limit movement thereof into the rib slot.

In testimony whereof I hereunto affix my signature.

WILLIAM NYE SECHLER.
